UNITED STATES PATENT OFFICE.

THOMAS J. WINANS, OF BINGHAMTON, NEW YORK, ASSIGNOR TO THE
NINETEEN HUNDRED WASHER CO., OF BINGHAMTON, NEW YORK.

OPERATING MECHANISM FOR WASHING-MACHINES.

No. 841,605.

Specification of Letters Patent.

Patented Jan. 15, 1907.

Application filed December 1, 1904. Serial No. 235,028.

To all whom it may concern:

Be it known that I, THOMAS J. WINANS, a citizen of the United States, residing at Binghamton, in the county of Broome and State 5 of New York, have invented certain new and useful Improvements in Operating Mechanism for Washing-Machines, of which the following is a specification.

My invention relates to improvements in 10 operating mechanism for washing-machines, and has for its object the provision of mechanism of this character which may be operated by connections from city water-mains or other water connections under pressure to 15 drive the operating-motor, or the operating mechanism may be driven by other power. The washing-machine is simple in construction, compact, and of a size to be conveniently used in an ordinary kitchen or 20 laundry-room. As illustrated, a motor is shown as applied to a washing-machine, connection being made to the ordinary street water-main in a wash-room for driving the motor and the motor in turn operatively connected to the washing-machine-operating mechanism and also to a clothes-wringer located on the washing-machine.

The invention consists of a motor-driven mechanism, the rotary motion of the driving- 30 motor being changed to a reciprocating or longitudinal backward-and-forward revolving motion of the washtub on its central support. The rotary motion of the motor may also be imparted to the rolls of a clothes- 35 wringer used in conjunction with the washing-machine.

The invention further consists in certain 40 novel features of construction and combinations and arrangements of parts, as described in the following specification, more fully pointed out in the claims, and as illustrated in the accompanying drawings, in which—

Figure 1 illustrates the complete embodiment of my invention, showing the operating mechanism of the washing-machine connected to a domestic motor operated by water-pressure from the street-main. Fig. 2 is a plan view of the washtub-swinging mechanism adapted to impart a forward and reverse oscillatory movement to the tub, showing also the two standards or uprights in section. Fig. 3 is a broken sectional detail view, enlarged, of the central tub support or bearing. Fig. 4 is an inverted view of the tub-

supporting frame, showing a projection on 55 one of said frame-forks and an arm projecting from the central support, against which arm the projection is adapted to engage or strike to aid in reversing the swing of the tub. Fig. 5 is an enlarged elevation of the gearing, 60 shaft, and crank-arm of the driving mechanism as seen from the left in Fig. 1. Fig. 6 is a cross-section on line 6 6, Fig. 5. Fig. 7 is a detail of the reciprocating rod and its connection with the rotary connecting-shaft and 65 crank of the operating mechanism. Fig. 8 is a broken sectional detail showing manner of holding the washtub to the frame.

The motor for operating the mechanism of the washing-machine has no essential bearing and forms no part of the present invention; but I illustrate a water-motor A, driven by pressure from a spigot B. The motor has a belt wheel or pulley C on the outside thereof, which is connected by a belt or rope D to 75 the large belt wheel or pulley 1 of the washing-machine-operating mechanism.

Pulley 1 is journaled on shaft J, located in bracket K, which bracket is attached to one of the uprights L of the frame M of the washing-machine. Wheel 1 and its shaft J impart motion to the series of driving-pinions 2 3 4 6 5 in the order named, and the shaft 7 of the wheel or pinion 6 carries a bevel-gear 8, which meshes with bevel-gear 9, located on 85 the shaft 10. All the pinions and gear-wheels are carried in bearings on bracket K. It will thus be seen that the motor, through the above-described connections and gearing, imparts motion to the rotary shaft 10. The 90 lower bearing for shaft 10 consists of the bracket 11, located in the corner at the base of the upright L and frame M. At the extreme lower end the shaft 10 has clamped thereto a crank-arm 12, said arm being split 95 at one end and provided with a clamping-screw 13, and by this means the crank-arm is rigidly connected to the shaft 10 and revolves therewith. At this point in the mechanism the rotary movement is changed to a reciprocating or oscillatory motion, and the reciprocating motion is utilized to swing the tub N horizontally forward and then in reverse direction on its central support.

Loosely seated in the crank-arm 12 at its 105 free end is the pin 14, having a head resting on the arm 12. This pin has an opening 15 therethrough, through which is passed the re-

ciprocating rod 16. A cut-away portion 17 is provided on the upper side of the rod 16, and beneath the rod and also in opening 15 is pushed the spring-cotter 18, the pressure 5 from the cotter tending to hold the cut-away portion 17 up against the top of the opening 15, thus holding the rod 16 rigid with relation to pin 14. From this construction it will be observed that when shaft 10 is ro- 10 tated or revolved it swings the crank-arm in a circle, and the pin 14, being loosely held in the arm, travels in a circle about the shaft and imparts a reciprocatory motion to rod 16.

Rod 16 is connected at its inner end to the 15 pivoted lever 19, and said lever is loosely mounted upon the central vertical shaft or support 20 and is free to turn thereon except when under conditions as will be described. Shaft 20 has a lower bearing in the bearing-bracket 21 and at the upper end of said bracket has a ball-bearing 22, the bracket being suitably supported in the frame M. At 20 its upper end the shaft 20 is provided with a rigid spider or multiple-armed frame 23, and 25 these two members—shaft 20 and spiders 23—rotate together. The spider 23 is located directly above the pivoted lever-arm 19, and one of the arms of the spider has at its end a raised lug 24, adapted to fit and engage in the 30 recessed bracket 25, located on the under side of the bottom of the washtub N.

A connection is formed between one of the arms 23 and pivoted lever 19 by means of the springs 26 26, which are attached at 27 27 to 35 the lever-arm and also hooked into the lugs 28 on the arm 23. Thus while the spider and lever-arm are not rigidly connected together they are so connected by the springs 26 that when the lever is moved on its pivot motion 40 is imparted to the spider through the springs, and the spider, being connected to the tub N by lug 24 and bracket 25, motion is also imparted to the tub when the lever is moved. In utilizing this spring connection advantage 45 is gained, in that while swinging forward the tub may be reversed in its movement without shock or jar, the springs acting as a buffer to take up any shock or jar due to reversal of the motion. This spring-buffer applies 50 principally to the reciprocating mechanism itself. The tub also has an arrangement of springs whereby the momentum of the tub is absorbed, and a reversal of movement may be accomplished without loss of power and also 55 without shock or jar.

Located directly below the lever 19 and surrounding the support 20 I employ the two-armed sleeve 29, having connected thereto the two springs 30, the outer ends of the 60 springs being in turn hooked to the brackets 31, secured to the frame M. On the under side of one of the spider-arms 23 I provide a projection 32. (See Fig. 4.) When the spider 23, carrying the tub, is swung around 65 its center, the projection 32 will engage first

one edge 33 and then the other edge 33 of the arms of sleeve 29. When either of these arms is engaged by the projection 32, the springs 30 30 will give in one direction or the other and sleeve 29 will rotate slightly 70 around the support 20, thus taking up the momentum of the parts and aiding in the reversal of movement of the tub and reciprocating parts of the mechanism.

The clothes-wringer (indicated at 34) may 75 also be operated from the motor through pulley C, belt D, wheel 1, and gears 2, 3, 4, 5, and 6 and gear 35. Gear 35 is journaled in the groove 36 of the bracket K and is adapted to engage with the gear 37, connected to 80 one of the rollers of the clothes-wringer. When the motor is in operation and the gear 37 meshing with gear 35, the wringer will be operated. The wringer may be attached to the washing-machine frame by clamping-screws 38, as indicated in Fig. 1.

In operation soiled clothes are placed in the tub, together with water and cleansing compound. The water-motor drives pulley C, belt D, pulley 1, and the series of gears, 90 which impart motion to the shaft 10 and crank 12, reciprocating the rod 16, which pulls and pushes the pivoted lever 19 back and forth. Lever 19 imparts motion to the spider 23, and with every rotation or revolution of the shaft 10 and crank 12 the tub is moved forward and reversed through the described connections, the springs acting to produce the results at reversal, as described. 95

Having thus fully described my invention, 100 what I claim is—

1. The combination with a central support, reciprocating mechanism mounted on the support and provided with shock-absorbing means, of a reciprocating rod connected 105 to said mechanism, and gear connections for operating the rod.

2. The combination with a central support, of yielding reciprocating mechanism mounted on said support, a reciprocating rod 110 connected to said mechanism, a rotary shaft and crank connected thereto, and a series of gears to operate the shaft.

3. The combination with a central support, of a supporting-spider mounted to oscillate upon said support, springs located in the spider to absorb the jar of the oscillations, a reciprocating rod connected to the spider, rotary shaft and crank connected thereto, and means for operating said shaft. 115

4. The combination with a supporting-post, of a spider adapted to oscillate with said post, shock-absorbing springs carried by the spider, a rod for oscillating the spider, and a series of gears for operating the shaft. 120

5. The combination with a support and a shaft mounted thereon, of a spider supported by said shaft, a lever loosely journaled on the shaft, springs connecting the lever to said spider, a rod and connections for reciprocating 125

ing said lever, a collar journaled on the shaft and adapted to be contacted by the lever, and springs limiting the motion of the collar, so that the same forms a yielding abutment to the lever.

5 6. The combination with a support and a spider adapted to oscillate thereupon, a lever arranged on the support, flexible connections between the spider and lever, a rod for oscil-

lating the lever, and a yielding abutment to limit the motion of the lever.

In testimony whereof I affix my signature in presence of two witnesses.

THOS. J. WINANS.
